UNITED STATES PATENT OFFICE.

JOHN C. LINCOLN, OF CLEVELAND, OHIO.

ELECTRICAL BOND FOR RAILWAY-RAILS.

1,261,140.

Specification of Letters Patent.

Patented Apr. 2, 1918.

Application filed February 25, 1916. Serial No. 80,384.

To all whom it may concern:

Be it known that I, JOHN C. LINCOLN, a citizen of the United States of America, residing at Cleveland, in the county of Cuyahoga and State of Ohio, have invented certain new and useful Improvements in Electrical Bonds for Railway-Rails, of which the following is a specification.

My invention relates to improvements in electrical bonds for railway rails, and has for its object the provision of a cheap, simple and readily attachable bond adapted to insure the maximum electrical conductivity between abutting rail ends.

15 The device of my invention comprises a plurality of metallic laminae, which preferably are strips of copper superposed upon one another, and held firmly united by a three-sided or approximately U-shaped clamp, embracing each end of the metallic laminae, and affording an extended base or footing for augmenting the contact surface of the bond.

20 My invention will be more readily understood by making reference to the accompanying drawings, wherein:—

Figure 1 is a view in vertical section of a rail joint with the attached bond fused or cast-welded upon the head thereof.

25 Fig. 2 is an end view of the preferred type of terminal clamp.

Fig. 3 is a view in side elevation of the bond.

30 Fig. 4 is a view in side elevation of a rail joint bonded with my improved bond, and

Fig. 5 is a top view of a similar rail joint with the bond brazed or otherwise secured thereon.

Throughout the several figures of the drawings, I have employed the same character of reference to indicate similar parts.

35 Figs. 2 and 3 show the essentials of my improved rail bond, which comprises a plurality of copper strips α , of substantially even width, bent into U-shape, and united by means of terminal clamps b , b . These clamps are three-sided and have extended bases or footings b' , at the extremities of their side arms, which arms are of such length as to bring their bases flush with the rear edges of the copper laminae α . In other words, the terminal clamps are approximately U-shaped in cross-section, and respectively afford recesses between the side

arms, of such depth, as will accommodate the copper laminae, when positioned edge-wise therein.

These terminal clamps are of such gage, that the sides thereof may be compressed by a suitable punch, as at b'' , whereby the terminals of the laminae are closely gripped and held by the side arms of the clamps, while leaving the rear edges of the laminae free, to be brought into contact with the respective rail ends.

45 In practice these rail bonds are constructed in pairs; being wound from a single strip of copper upon a mandrel, approximately of flattened O-shape, intermediately clamped by three-sided clamps, such as herein shown, and then sawed in two, thus forming two of such rail bonds. These bonds are thus formed from superposed and terminally clamped but otherwise unconnected laminae, so that the expense of welding or 50 soldering the terminals is obviated by the firmly gripping U-shaped members.

55 Preferably, these rail bonds are united to the rails, by clamping them in the position shown in Figs. 1, 4 and 5, whereupon suitable means for fusing the upper portions of the terminals, such as an electrical arc or acetylene flame are applied to the terminals of the bond, and if desired, additional material c , may be fused upon the terminals 55 and upon the rail ends, so as to augment the contact surfaces or heads, as required. This operation may best be practised as set forth in my patent application, Serial Number 783,992, August 9, 1913, (Patent Number 1,183,992); but forming no part of my present invention, it does not require further explanation herein.

60 It is also apparent that the terminals and laminae of my improved bond may be soldered, brazed or otherwise secured to the rail ends, and still attain the objects of my invention. As shown in the assembled figures of the drawings, the bond in question is positioned to bridge the electrical gap 65 between the abutting rail ends, with the edges of the copper laminae individually engaging the surfaces of both rail ends, while the sides and extended footings or bases of the clamps, being in the same plane, necessarily augment the contact surfaces of the bond terminals. Thus there is insured the 70 maximum of conductivity, since each indi-

vidual lamina is terminally connected edge-wise with both rails, while the conductivity of the mass, at each terminal, is augmented by the bodies of the respective terminal clamps, and the contact surfaces are further extended by their laterally expanded bases or footings, b' .

In Figs. 1 and 4, the contact heads of the bond are augmented by additional copper 10 fused upon the rail ends and the bond terminals, while in Fig. 5, the bond is shown without this adjunct, and is assumed to be brazed, soldered or otherwise secured directly to the rail ends.

15 In addition to the lateral punchings b'' , I preferably subject each terminal clamp to a transverse frontal punching operation. This drives the metal of the clamp at d , d , edgewise into approximately all of the 20 laminae, and thereby maintains the entity of the bond, except under stress of a heavy blow, as well as augmenting the conductivity somewhat between the members of the device.

25 Having now described the preferred embodiment of my invention, I claim as new, and desire to secure by Letters Patent, the following:

1. In an electrical bond for rails, the combination with a plurality of metallic laminae, superposed one upon another and terminally gripped but otherwise unconnected, of U-shaped terminals gripping said laminae at their ends; said terminals having sides substantially the width of the laminae, and expanded bases, whereby enlarged contact surfaces, abutting the rails, are afforded, substantially as set forth.

2. A rail bond for electrically uniting 40 railway rails, comprising a plurality of superposed copper strips bent approximately to U-shape, and terminally gripped but otherwise unconnected and three-sided clamps respectively gripping and embracing 45 the terminals of said copper strips, but leaving their rear faces free or exposed, whereby said strips may more readily be individually united directly with the rail ends, substantially as set forth.

50 3. A rail bond for railway rails, comprising superposed and terminally gripped but otherwise unconnected copper laminae and securing terminals embracing said laminae at their ends, upon three sides only, whereby 55 they may more readily be united individually with the rail ends; said terminals having expanded base portions also adapted to be united with the rail ends, for affording

extended contact surfaces, substantially as set forth. 60

4. A rail bond for railway rails, comprising superposed and terminally gripped but otherwise unconnected copper strips of even width, and terminal clamps of heavy gage metal gripping said strips in position to be 65 engaged and make edgewise contact with the rail ends; said terminal clamps embracing the strips upon three sides only, and forcibly clamped about and uniting the ends of said strips, substantially as set forth. 70

5. A rail bond for electrically uniting railway rails, comprising a plurality of superposed and terminally gripped but otherwise unconnected metallic laminae, and terminal metallic clamps respectively mounted upon said laminae; said clamps being punched to upset the metal thereof and extend edgewise into the bodies of the laminae, substantially as set forth. 75

6. A rail bond for railway rails, comprising superposed and terminally gripped but otherwise unconnected copper laminae and metallic terminals embracing said laminae at their ends upon three sides; said terminals being frontally punched to force the bodies thereof edgewise into the laminae for securing the members firmly together, substantially as set forth. 80

7. An electric rail bond, comprising superposed and terminally clamped but otherwise unconnected copper laminae, and metallic terminals of relatively heavy gage embracing said laminae at their ends in direct engagement with their edges frontally, said terminals being transversely punched frontally to force the respective bodies thereof into substantially all of the laminae for securing them rigidly together, substantially as set forth. 90

8. A rail bond for railway rails comprising a plurality of metallic laminae and terminals therefor; said laminae being superposed and firmly clamped together by said terminals but otherwise unconnected; said terminals embracing said superposed laminae on three sides, leaving one side, comprising the edges of the laminae, exposed for attaching to the rails, so that the laminae may be individually united directly with the rail ends, substantially as set forth. 100

In testimony whereof I do now affix my signature in the presence of two witnesses.

JOHN C. LINCOLN, [I. S.]
